UNITED STATES PATENT OFFICE.

ALFRED STEINHAUSER, OF PHILADELPHIA, PENNSYLVANIA.

STUDDING-FASTENER.

1,089,878.

Specification of Letters Patent. Patented Mar. 10, 1914.

Application filed April 9, 1913. Serial No. 760,015.

To all whom it may concern:

Be it known that I, ALFRED STEINHAUSER, a citizen of the United States, residing in the city and county of Philadelphia, State 5 of Pennsylvania, have invented a new and useful Studding-Fastener, of which the following is a specification.

My invention consists of a fastener for studding, struts, braces or similar elements 10 of frame construction which will dispense with the use of nails and the consequent danger of splitting the wood of the members to be joined and the uncertainty of driving nails obliquely through such members.

It further consists of such a fastener having prongs projecting from its body-portion and adapted to be driven into one member of the frame-construction and prongs 20 projecting in the opposite direction at its ends and adapted to be driven into the member to which said former member is to be joined.

It further consists of such a fastener in 25 which the ends of the body-portion are bent from the plane of the body-portion to bring the points of the end-prongs into such plane.

It further consists of other novel features 30 of construction, all as will be hereinafter fully set forth.

The annexed drawings and the following description set forth in detail one mechanical form embodying the invention, such detail construction being but one of various 35 mechanical forms in which the principle of the invention may be used.

In said annexed drawings—Figure 1 represents an elevation of a portion of a wall or partition and of a floor, illustrating the 40 application of my improved fastener. Fig. 2 represents a section of a stud and strut with the fastener in place to have its end-prongs driven into the stud. Fig. 3 represents a similar view of said parts with the 45 end-prongs driven home. Fig. 4 represents a perspective view of one form of the fastener. Fig. 5 represents a plan view of another form of the fastener.

Similar numerals of reference indicate 50 corresponding parts in the figures.

Referring to the drawings, the reference numeral 1 indicates flooring or a portion of a floor-joist, upon which rest two studs, 2, or similar uprights, laterally braced by a 55 strut or brace, 3, and all joined by means of my improved fasteners, 4. Said fas-

teners are preferably formed from sheet-metal, stamped out to form a flat body-portion, 5, having prongs, 6, struck out from it in one direction. Said prongs may all be 60 struck out from the body of said body portion, as illustrated in Fig. 4 of the drawings, or some of the prongs may be struck out from the side-edges of the body-portion, as illustrated in Fig. 5 of the drawing. 65

The fastener is preferably longer than it is wide, and the ends or extensions of the plate are preferably weakened, as by triangular openings, 7, cut out of the metal, to allow of the ends being bent, and said ends are preferably outwardly narrowed 70 and have end-prongs, 8, bent in planes at substantially right angles to the planes of the ends to project in a direction opposite to that of the body-prongs. The side-edges 75 of the several prongs are preferably formed with notches, 9, to provide bite in the wood when driven into the same. The ends are preferably so bent that the points of the end-prongs will be in about the plane of 80 the face of the body-portion.

In practice, the fastener is placed against the ends of the stud, strut, brace or whatever frame-member the fastener is employed with, and the body-prongs are driven into 85 such end. As the end-prongs are in about the plane of the face of the body-portion, owing to the bend of the ends, the end of the stud or whatever member it may be can be squarely placed against the face of the 90 floor or stud or other member to which it is to be joined, whereupon the end-prongs can be driven into said member, straightening the plate and securely joining the two frame-members. 95

By the use of this fastener, several frame-members can be securely joined without the use of nails obliquely driven through one member into the other, thus disposing of all danger of splitting such members by the 100 oblique nails, and a square and accurate joint will be made.

The use of the fastener simplifies labor, as one fastener takes the place of several nails, the body-prongs are driven into the 105 end of the frame-member in one operation, and the end-prongs are driven into the face of the other frame-member in one operation, each. The fastener may be again removed by prying the end-prongs out and 110 bending the ends to free such prongs from the face of the frame-member.

The construction of the fastener is exceedingly simple and inexpensive, as it is made from one single piece of sheet-metal and can be stamped out by a very simple operation.

5 Other modes of applying the principle of my invention may be employed for the mode herein explained. Change may therefore be made as regards the mechanism thus disclosed, provided the principles of construction set forth respectively in the following claims are employed.

Having thus described my invention, what I claim as new and desire to secure by Letters Patent, is:—

15 1. A fastener for studding and similar frame elements, comprising a body-portion having prongs projecting in one direction only and extensions on said body portion having prongs projecting in one direction 20 only and in the opposite direction to the body prongs.

2. A fastener for studding and similar frame elements, comprising a body-portion having prongs projecting in one direction 25 and ends bent out of the plane of said body-portion and having end-prongs projecting in the opposite direction.

3. A fastener for studding and similar

frame elements, consisting of a single plate 30 of sheet-metal forming a flat body-portion having prongs struck out from it to project in one direction and end-portions bent out of the plane of said body-portion and having prongs struck out from them to project in the opposite direction.

35 4. A fastener for studding and similar frame elements, consisting of a single plate of sheet-metal forming a flat body-portion having prongs struck out from it to project in one direction and weakened end-portions bent out of the plane of said body-portion and having prongs struck out from them to project in the opposite direction.

40 5. A fastener for studding and similar frame elements, consisting of a single plate 45 of sheet-metal forming a flat body-portion, prongs projecting therefrom in one direction only, and weakened extensions on said body portion having prongs projecting therefrom in one direction only and in the opposite direction to the first-mentioned prongs.

ALFRED STEINHAUSER.
